TOY MOBILE ROCKET LAUNCHER

Allan J. Alvaney, Arlington Heights, Ill., assignor to Sears, Roebuck and Co., Chicago, Ill., a corporation of New York

Filed Dec. 1, 1960, Ser. No. 63,055

Term of patent 7 years

(Cl. D34—15)

Fig. 2.

FIG. 1 is a front perspective view of the toy mobile rocket launcher showing my new design, and

FIG. 2 is a rear perspective view of same.

The rocket shown in broken lines in the drawings is for illustrative purposes only.

I claim:

The ornamental design for a toy mobile rocket launcher, substantially as shown and described.
